UNITED STATES PATENT OFFICE.

JACOB HUETHER, OF NEW YORK, N. Y., ASSIGNOR TO ROBERT GAIR COMPANY, OF BROOKLYN, NEW YORK, A CORPORATION OF NEW YORK.

MACHINE FOR APPLYING TAPES TO BOXES.

No. 838,413.

Specification of Letters Patent.

Patented Dec. 11, 1906.

Application filed May 29, 1905. Serial No. 262,726.

To all whom it may concern.

Be it known that I, JACOB HUETHER, a citizen of the United States, and a resident of New York, borough of Brooklyn, in the county of Kings and State of New York, have invented a new and useful Machine for Applying Tapes to Boxes, of which the following is a specification.

This invention relates to applying the tape handles to ice-cream, confectionery, and other boxes made out of paper or cardboard and like materials.

In taping boxes for the purpose of supplying them with handles it is necessary that the tapes should be cut to the proper lengths, the boxes perforated with holes to receive the ends of the tapes, sufficient slack left to form the handle, and the ends passed through the holes, turned up against the inside of the box, and secured thereto by an adhesive. Heretofore this taping has been done by manual labor, and a number of operations have been required, which involved considerable manipulation of each box. This materially increased the cost of manufacturing these articles, and the output was relatively small to the cost of manufacture, and there was more or less want of uniformity in the finish of the articles.

The object of this invention is, first, to reduce the cost of applying and fastening the tapes to these boxes by dispensing with manual labor in the operations of placing the tapes in position, perforating the boxes, and inserting and gluing the ends to the inside of the box; second, to enable the taping to be done much more rapidly than has heretofore been possible, and thus greatly increase the output of the taped boxes in a given time; third, to turn out the work much more uniform in finish and with tapes fastened in a more secure and permanent manner and to lessen the waste of material which is inevitably associated with manual labor in this class of work.

By this invention the box before being glued up is laid upon a table by an operator, and the part of the tape to form the handle is drawn across it by a gripper, which takes it from a roll, and a slack portion for the handle is drawn up, and the length of tape for the handle and the attached ends cut off. The ends are turned at right angles to the handle por-

tion, and a punch perforates the box and inserts these ends through the holes simultaneously. The glue is applied to the under side of the box, and a device turns the ends up and presses them against the glue and lays them down against the under side of the box and secures them thereto.

In the accompanying drawings, Figure 1 represents a front elevation of the machine; Fig. 2, a rear elevation of the same. Fig. 3 is a plan. Fig. 4 is an end elevation looking from the right-hand end of the machine. Fig. 5 is a vertical cross-section of the machine, taken on line A A of Fig. 1 and looking from left to right. Fig. 6 is a vertical cross-section of the machine, taken on line B B of Fig. 1. Fig. 7 is a cross-section of the machine, taken on line C C of Fig. 1 and showing one of the devices for turning the ends of the tape and perforating the box in its normal position and means for operating the same. Fig. 8 is a similar view with the devices for turning the ends of the tape and punching holes in the box in their proper positions. Fig. 9 represents a sectional side elevation of the knife for severing the tape and the device for operating the same, the section being taken on line D D of Fig. 1. Fig. 10 represents a sectional side elevation of the devices for holding the ends of the tape after the part for the handle has been cut off and the devices for operating the same, the section being taken on line E E of Fig. 1. Fig. 11 is a side elevation of one of the grippers and a rack-bar to which the same is attached, and Fig. 12 is a plan of the same. Fig. 13 is a diagrammatic representation of the operation of the machine. Fig. 14 is a longitudinal section through the table, the box on the same, the devices for turning the ends of the tape, and the devices for making the slack for forming the handle, these devices being shown in their position just before the punches descend and perforate the box and insert the ends of the tape. Fig. 15 is a top plan of the same. Fig. 16 represents the devices shown in Fig. 14 in the position they occupy after the ends have been turned and the punches have perforated the box and inserted the ends of the tape. Fig. 17 is a top plan of the same. Fig. 18 is a sectional view of one of the devices for turning the ends of the tape, the punch, the box, and the table.

taken on line E' E' of Fig. 16. Fig. 19, Sheet 7, represents the face of one of the devices for turning the ends of the tapes.

Referring to the drawings, F designates a table which is supported on legs G G, braced by longitudinal bars H and transverse bars I. J J' are standards bolted to the table F, that have at their upper ends bearings K L for a driving-shaft, M on which fast and loose pulleys N O, a balance-wheel P, and a driving-pinion Q are mounted. The standard J' also carries the side bearing R in a front projection thereof. At the opposite or right-hand end of the table there is a standard S, which has a bearing T at the top in line with the bearing R, and a rear lateral projection U, provided with a bearing V in line with a bearing W in a rear projection U' of the standard J'. In the bearings R T at the front of the machine a counter-shaft *a* is supported, and in the bearings V W at the rear of the machine a second counter-shaft *b* is supported. The shaft *a* at the left-hand end of the machine carries a spur-wheel *d*, that meshes with the driving-pinion Q, and at the right-hand end of the machine this same shaft carries a sprocket-wheel *e*, which is connected, by means of a sprocket-chain *f*, with a sprocket-wheel *g* on a shaft *h* below the table. The counter-shaft *b* carries at the right-hand end of the machine a grooved cam 1. The fork 2 on the counter-shaft *b* is provided with a rack-bar 3, that passes down through a guide-slot in the table and carries a roller 4, that runs in the groove 5 of the cam 1. The rack-bar 3 engages a rack-pinion 6 on a transverse shaft 7 in bearings under the table. The groove 5 of the cam is adapted to move the forked rack-bar 3 up and down, and thereby through the pinion 6 turn the shaft 7 to the right and left.

8 is a pinion on the shaft 7, the upper periphery of which runs in a mortise 9 in the under side of the table, and its teeth project through an aperture into a longitudinal groove 10 in the upper side of the table and engages the rack 11 on the under side of a bar 12 in the groove, whereby when the shaft is turned by the rack-bar 3 and the rack-pinion 6 the pinion 8 moves the bar to the right and left alternately. The bar 12 carries two grippers 13 14, situated, respectively, to the right and left of the middle of the machine. Each gripper consists of a fixed lower jaw 15 on a plate 16, secured to the rack-bar 12, and a movable upper jaw 17 on a lever 18 which opposes the lower jaw 15. The lever 18 has its fulcrum on a pivot 19, passed through projections of the plate 16, in which a projection on the under side of the lever is inserted. The upper movable jaw is closed against the lower fixed jaw by means of a spiral spring 20. The rear end of the movable jaw is provided with a toe 21 and a V-shaped notch 22. The plate 16 has two perforated

guides 23 23 at its rear end, in which is inserted the stem of a spring-bolt 24, which is in line with the V-shaped notch 22. The movable jaw is held open by the bolt 24 engaging the V-shaped notch 22, and when released from the bolt it is closed by the spiral spring. The rear end of the bolt-stem has a right-angular projection that forms a hook 25, which projects beyond the rear side of the rack-bar 12. The gripper-bolts are drawn back to release the movable jaws by means of right-angular fingers 26 27 when the hooks 25 are carried against the said fingers by the movement of the rack-bar 12 to the left, whereby the hooks 25 are carried against the said fingers and the bolts drawn back out of the notches in the ends of the levers of the movable jaws. These jaws are opened by means of forks 28 29 on the counter-shaft *b*, which are moved up and down by means of cams 30 31 on said shaft operating against rollers 32 33 on the said forks and spiral springs 34 35. The shafts are passed down through guides in brackets 36 37 and carry right-angular arms 38 39, which when the forks are moved downward strike against the toes 21, and thereby throw the rear end of the levers down, opening the jaws and bringing the V-shaped notches in line with the bolts, which enter the same, and thus hold the movable jaws open. Between the standards J' S and on brackets 40 40 on said standards a plate 41 is supported and fastened, which at the middle portion 42 is projected downward and provided with vertical perforations 43 43 and a central angular arch 44.

45 45 are spindles which are inserted in the perforations 43 43 and are adapted to move up and down therein. The spindles are provided with a central bore 46. This bore does not pass through the lower end of the spindle; but in the bottom of the said bore a rectangular slot 47 extends through to the end of the spindle. A pin 47^a is inserted in the bore and carries at its lower end a rectangular punch 48, the lower end of which extends into the slot 47, and its upper end is connected with the arm 49 of a Z-shaped bracket 50, the lower horizontal arm 51 of which is held in the vertical slot of the guide 52, fastened to the face of the part 42 of the plate 41. The stems or shanks 53 of the spindles 45 are passed through perforations in a yoke 54, which rests upon the shoulders between the spindles and their stems. The yoke 54 is carried on the threaded stem 55 of a fork 56, the stem being passed through a central perforation 57 in the yoke and is held between clamping-nuts 58 58, screwed on the stem. The fork 56 is placed upon the shaft *a*, which carries a cam 59, that bears against the roller 60 on the fork, and the upper end of the fork is fitted with a plate 61, which is hung on the lower end of a spiral spring 62,

the upper end of which is fastened to an arm 63, projecting from a standard 64. 65 65 are brackets bolted to the part 42 of the plate 41. These brackets are curved upward and backward toward the arm of the machine and are provided with bearings 66, in which a shaft 67 is supported. This shaft carries cams 68 68, and forks 69 69 are also placed on said shafts, and the bars 70 70 of these forks are passed through guides 71 in plates 72, fastened to the rear side of the plate 41. The stems 53 53 of the spindles have pinions 73 73, which rest on the yoke 54 and are fastened to the stem by means of keys 74. These pinions are engaged by the rack-teeth on the stems of the forks 69. The forks are fitted with cross-plates 75, which are hooked to spiral springs 76, the other ends of said springs being fastened to the upper ends of brackets 77, connected with the table. Reciprocating motions are given to the fork by means of the cams 68, bearing against rollers 78 on the forks, and spiral springs 76, and by the reciprocating motion the spindles, 25 through the rack-bars and pinions, are rotated to the right and left as the forks move back and forth. Midway between the pinions 73 73 and in front of the fork 56 an inverted-T-shaped plate 79 is hung upon the lower end of a spiral spring 80, the upper end of which is suspended from the arm 63. The arms of the T-shaped plate are turned up and passed through perforations in the arms 51 of the brackets 50 50. The brackets 50 50 are thus suspended between the guides 52 52. Cams 81 81 are mounted on the counter-shaft *a* over the horizontal arms 49 of the brackets 50. When the low points of the cams are above the arms 49 of the brackets 50, the 40 spring 80, through the plate 79, lifts the brackets 50 50 up, and the brackets, being connected with the pins 47^a in the spindles, withdraw the pin from the spindles, and thereby draw the punches up in the spindles, as shown by Fig. 7; but when the high part of the cam bears against the arms 49 of the brackets the brackets are forced down, and thereby the pins are driven into the spindles and the punches forced down out of the same, 45 as shown by Fig. 8. The downward motion of the spindles from the position shown by Fig. 7 to the position shown by Fig. 8 is brought about by means of the cam 59 on the counter-shaft *a*, which bears the fork 56 down, and thereby causes the yoke 54 to move the spindles downward to the position shown by Fig. 8. The downward movement of the spindles takes place before the cams 81 drive the punches down out of the spindles. The 50 pinions 73 73 are of sufficient length to retain their engagement with the rack-bars on the forks 69 when the spindles are moved downward, as shown by Fig. 8. The spindles are rotated a quarter-turn in one direction from the right to left as they move downward. In

the ends or faces of the spindles there is on one side a slot 82, the bottom of which is inclined downward toward the center of the spindle, and on the opposite side there is a rectangular notch 83. As will be seen by Fig. 7, when the spindles are in their upper position these slots are at the front and rear sides of the spindles; but during their descent they make one complete revolution and come to rest in the same position as when they started when their downward movement began, as shown by Fig. 8. The device for taking up the tape to form the slack or handle part consists of a horizontal arm 84 on the lower end and a vertical bar 85, having a finger 86, which projects at right angles from the arm 84 under the arch 44 of the downward-projecting part 42 of the plate 41. The bar 85 is connected with a fork 87 on the counter-shaft *a*, which is operated by a cam 88 on said shaft, the stem of the fork passing through the guide in the plate 41. The bar 85 is hung on the lower end of a spiral spring 90, suspended from an arm 91, connected with the standard 64. By the movement of the fork the finger 86 is carried down to the table or lifted to the position shown by Figs. 14 16 in the arch 44. 85 90

92 is the knife for severing the tape, which is connected with the lower end of the stem 93 of fork 94, which is passed through a guide in the plate 41. The counter-shaft *a* is passed through the fork and carries a cam 95, by which the fork is moved downward, the upward movement being produced by a spiral spring 96, coiled on the stem of the fork between its shoulders and the plate 41. The knife acts in conjunction with a knife-edge 97 and on the end a right-angular arm 98, fastened to the table. The top of the 100 arm is provided with an inclined groove 99, (see Fig. 13,) which forms a guide for the tape. 105

The tape is held after it is cut off by means of a spring-clamp 100 to the left of the knife. 110 This clamp is passed through a guide 101, screwed in a socket-piece 102, fastened by means of a set-screw 103 to a fork 104, through which the counter-shaft *a* passes, the stem being passed through a guide in the 115 plate 41. The fork is moved downward by means of a cam 105 on the counter-shaft *a* and upward by a spiral spring 106 on the stem of the shaft between the shoulders of the fork and the plate 41. The clamp acts 120 against the block 107 on the table. Under the table there is a shaft 108, held in bearings 109, suspended from the table. This shaft carries a gear-wheel 110, that meshes with a pinion 111 on the shaft *b*. On the shaft are 125 collars 112 113, each of which carries a glue-brush 114 and a wiper 115. In the table immediately above the collars there are mortises 116 117, arranged transversely of the table and immediately under the spindles 45 130

45. When the shaft 108 revolves, the brushes are carried up in the mortise and the wipers follow immediately behind the glue-brushes. On the shaft *h*, in line with the brushes 114 115, snail-wheels 118 119 are mounted on the shaft *h*. These snails revolve in a glue-tank 120 and take up the glue therefrom. The adjustment of the snail-wheels is such that the glue-brushes come in 10 contact with the high part thereof and take the glue therefrom. The wipers 115 pass the low part thereof, and thus do not take the glue.

The gripper 14 aids in drawing the tape off 15 the roll. It will be observed that it is connected with the bar 12 and is opened by means of the fork 29 at the left-hand end of the machine, and the bolt is drawn back by the hook on its end coming in contact with the 20 finger 27 when the bar is moved to the left. The diagrammatic representation of the operation of the machine, Fig. 13, shows this gripper in three positions. When the gripper 13 moves to the right and draws the tape over the box, 25 gripper 14 is in its extreme left-hand position (shown by the dotted lines) and closed on the tape and draws the tape off the roll as it is moved to the right, and when it reaches its extreme right-hand position (shown by the dotted lines) next to the clamp 100 it is opened 30 by the fork 29, and the bolt enters the V-shaped notch in the movable jaw and holds it open, so that when the bar moves back to the left to cause the gripper 13 to slacken the 35 tape gripper 14 moves back to the position shown by the solid lines, but the jaw being open the tape slips through it. When, however, the bar moves to the left to carry the gripper to the point where it takes the end of 40 the tape from the arm 98, the gripper 14 is also moved back to its extreme left-hand position, (shown by Fig. 13,) and as its hook comes in contact with the finger 27 the bolt is drawn back, and thus releases the movable 45 jaw, which closes on the tape, as shown. It will be understood from the foregoing that the gripper 14 has no other function than to draw the tape off the roll, so that the gripper 13 can the more easily and without liability 50 of displacing the tape or stretching it carry it across the box and lay it in its position thereon under the spindles.

At the beginning of the operation of the machine the gripper 13 is at its extreme position to the left—that is, in line with the knife-edge 97—and the jaws are open so that the arm is between them, as shown by the diagram Fig. 13. The tape 121, which is wound on the reel 122, is drawn up and its 55 end carried through the gripper 14, which is at its extreme left-hand position, as shown by Fig. 13, thence under the clamp 100, thence up the inclined groove 99 in the arm 98, and between the jaws of the gripper 13, 60 which, as before stated, are open and in line

with the end of the arm 98. When the machine starts, the gripper 13 moves to the right and the upper jaw, which is roughened on the under side, pulls the tape off the arm, and it immediately closes on the tape. The 70 clamp 100 is also moved up when the gripper seizes the tape, and the movement of the gripper being continued it draws the tape with it until it passes the right-hand spindle 45 to the position indicated by the dotted 75 lines, Fig. 13. A box 123 having been placed upon the table with the parts to which the tapes are to be attached under the spindles, when the gripper moves to the right it lays the tape on top of the box and under the 80 spindles. When the gripper reaches the point indicated by the dotted lines, Fig. 13, the spindles are moved downward on top of the tape and hold it against the box. At this point the gripper 13 moves to the left to 85 the position indicated by the solid lines, Fig. 13, and at the same time the finger 86 is moved upward and draws the tape with it as it is slackened by the movement of the gripper 13 to the left. The connection between the tape under the spindle 45 and that on top of the arm is not severed at this stage. Hence when the finger 86 is moved upward it draws the tape as it is slackened from under the spindle next to the gripper; but, the 90 other end being held by the clamp, which descends when the gripper 13 reaches its extreme right-hand position, the tape cannot be drawn from under the spindle next to the clamp. When the gripper 13 moves to the 95 left hand and stops in the position indicated by the solid lines, Fig. 13, the fork 28 descends, and its arm 38 strikes the toe 21 and presses the lever down until the bolt enters the V-shaped notch, and thus the gripper 100 jaw is opened and locked, leaving the end 124 free. At the same moment the knife 92 descends and severs the tape, leaving the end 125 free. The position of the tape and the 105 spindles and the finger at this stage is indicated by Fig. 14. The spindles are next rotated in the direction of their arrows, Fig. 14, and as the part 126 between the spindles is drawn up at a sharp angle the edges in the 110 rectangular notches 83 are between the sides 115 of said notches. The edges of the ends 124 125 are also between the sides of the inclined notches 82 82. When the spindles are rotated, the sides of the notches bear against the edges of the tape, thereby turning the 120 part 126 of the tape between the spindles back and the ends 124 125 forward. By this operation the part 126 of the tape is slipped off the finger 86 and the ends of the tape are drawn around at right angles to the position 125 shown by Figs. 16 and 17, where is shown clearly the tape clear of the finger 86 and the ends of the tape projecting to the front. When this operation is concluded, the glue-brushes are brought in contact with the un- 130

der surface of the box through the mortises, and they apply the glue to the under side of the surface of the box immediately under the spindles. When the glue-brushes pass, the 5 punches 48 are driven down against the parts of the tape under the spindles and simultaneously perforate the box and drive the ends of the tape down through the perforations, as shown by Fig. 16. The punches 10 are immediately withdrawn and the wipers 115 arrive in the mortises and bear against the ends of the tape, turn them up at right angles to the box, and fix them thereto by pressing them against the glue on the under 15 surface.

I claim—

1. In a machine for applying tapes to boxes means that takes the end of the tape, means for moving the said means to cause it to lay 20 the tape on the part of the box to which it is to be attached, means for holding the tape at the points where its ends are to be fastened to the box, and means for moving the means that carry the tape back a limited distance 25 to slacken the tape, substantially as specified.

2. In a machine for applying tapes to boxes means that takes the end of the tape, means for moving the said means to cause it to lay the tape on the part of the box to which it is 30 to be attached, means for holding the tape at the points where its ends are to be fastened to the box, means for moving the means that carry the tape back a limited distance to slacken the tape, and means for taking up 35 the tape between the means by which it is held on the box as it is slackened, substantially as specified.

3. In a machine for applying tapes to boxes a gripper that takes the end of the tape, 40 means for moving the gripper to cause it to lay the tape on the part of the box to which it is to be attached, means for holding the tape at the points where its ends are to be fastened to the box, means for moving the 45 gripper back a limited distance to slacken the tape, and means for holding up the tape between the means by which it is held on the box as it is slackened, substantially as specified.

50 4. In a machine for applying tapes to boxes means that takes the end of the tape, means for moving the said means to cause it to lay the tape on the part of the box to which it is to be attached, spindles which are adapted 55 to be moved against the tape after it is laid in position on the box and to hold it at the points where its ends are to be fastened to the box, means for moving back the means that carries the tape a limited distance to 60 slacken the tape, and means for taking up the tape between the means by which it is laid on the box as it is slackened, substantially as specified.

5. In a machine for applying tapes to boxes 65 means that takes the end of the tape, means

for moving the said means to cause it to lay the tape on the part of the box to which it is to be attached, means for holding the tape at the points where its ends are to be fastened to the box, means for moving back the 70 means by which the tape is carried a limited distance to slacken the tape, a finger over which the tape is laid located between the means by which the tape is held, and means for causing the finger to take up the tape as 75 it is slackened, substantially as specified.

6. In a machine for applying tapes to boxes a gripper connected with a bar, means for reciprocating the bar, means for opening the gripper to receive the end of the tape, means 80 for closing the gripper when the bar is moved to the right to cause the gripper to take the end of the tape and draw the tape over the box and lay it on the part of the box to which it is to be applied, means for holding the tape 85 at the points where its ends are to be fastened to the box, means for arresting the movement of the bar after the tape is laid on the box, means for moving the bar in the opposite direction to carry the gripper backward 90 to slacken the tape, and means for taking up the tape between the means by which it is held on the box as it is slackened, substantially as specified.

7. In a machine for applying tapes to boxes 95 a gripper connected with a bar, a cam for reciprocating the bar, means for opening the gripper when the bar is moved to the left, an arm on which the end of the tape rests that passes between the jaws of the gripper, 100 means for closing the gripper when the bar moves to the right, said gripper adapted to lay the tape on the part of the box to which it is to be applied as it is moved to the right, means for holding the tape at the points 105 where its ends are to be fastened to the box, means for moving the bar in the opposite direction after the tape is laid on the box and thus causing the gripper to slacken the tape, and means for taking up the tape between 110 the means by which it is held on the box as it is slackened, substantially as specified.

8. In a machine for applying tapes to boxes means that takes the end of the tape, means for moving said means to cause it to lay 115 the tape on the part of the box to which it is to be attached, rotatable and longitudinally-movable spindles having notches in their ends the notches of each spindle being diametrically opposite each other, means for 120 moving the said spindles downward against the tape after it is laid in position on the box to hold it at the points where its ends are to be fastened to the box, means for moving back the means that lays the tape on the box 125 a limited distance to slacken the tape, means for drawing the tape as it is slackened under the spindle next to the means that holds the end of the tape and takes up the slack between the spindles substantially as specified. 130

9. In a machine for applying tapes to boxes means that takes the end of the tape, means for moving the said means to cause it to lay the tape on the part of the box to which it is to be attached, rotatable and longitudinally - movable spindles having notches in their ends the notches of each spindle being diametrically opposite each other, means for moving the said spindles downward against the tape after it is laid in position on the box to hold it at the points where its ends are to be fastened to the box, means for moving back the means that lays the tape on the box a limited distance to slacken the tape, means for drawing the tape as it is slackened under the spindle next to the means that holds the end of the tape, means for taking up the slack between the spindles, means for cutting off the part of the tape held by the spindles, and means for rotating the spindles to cause them to turn the ends of the tape to a position at right angles to the part between the spindles and to disconnect the part between the spindles from the means by which the same is taken up, substantially as specified.

10. In a machine for applying tapes to boxes a table, a gripper, means for moving said gripper to the right and left on said table, means for opening and closing said gripper, an arm having a knife-edge at one end and a groove in the top in which the end of the tape is laid, a clamp for holding the said tape, means for opening the jaws of the gripper when it is moved to the left so that the said arm with the end of the tape lying thereon will pass between the jaws of the gripper, means for moving the gripper to the right, means for closing the jaws of the gripper when the gripper moves to the right to cause it to grip the end of the tape and draw the tape off the roll and lay it on the box to which it is to be attached, means for releasing the clamp, rotatable and longitudinally - movable spindles, means for moving said spindles against the tape after it is laid in position on the box and hold it at the points where its edges are to be fastened to the box, means for moving the gripper back a limited distance to slacken the tape, a finger between the spindles over which the tape is laid, and means for lifting the said finger as the gripper is moved backward to cause it to take up the slack between the spindles and draw the tape under the spindle next to the gripper that holds the end of the tape, substantially as specified.

11. In a machine for applying tapes to boxes means that takes the end of the tape, means for moving the said means to cause it to lay the tape on the part of the box to which it is to be attached, means for clamping said tape between the spindles and the roll after the gripper has laid the tape on the box, rotatable and longitudinally-movable

hollow spindles having notches in their ends the notches of each spindle being diametrically opposite each other, punches sheathed in said spindles and adapted to be moved through the ends thereof between the notches, means for driving the said punches out of the spindles, means for moving the gripper backward a limited distance to slacken the tape, a finger over which the tape is laid located between the spindles, means for causing the said finger to take up the tape as it is slackened, means for cutting off the tape means for rotating the spindles to cause them to turn the end of the tape at right angles to the part between them and disengage said part from the finger, means for driving the punches out of the spindles against the ends of the tape to punch the box and insert the ends of the tape in the box, substantially as specified.

12. In a machine for applying tapes to boxes a table having a longitudinal groove in the top, a rack-bar in said groove, means for reciprocating said rack-bar, a gripper fastened to the said rack-bar, means for opening the gripper when it moves to the left to adapt it to take the end of the tape, means for closing the gripper on the end of the tape, means for moving the gripper to the right to cause it to lay the tape on the part of the box to which it is to be attached, rotatable and longitudinally - movable spindles, means by which they are moved against the tape after it is laid in position on the box to hold it at the points where its ends are to be fastened to the box said spindles having notches in their ends the notches in each spindle being diametrically opposite each other, means for moving the bar to the left after the tape is laid on the box and the spindles have secured the same to cause it to carry the gripper a limited distance to slacken the tape, means for taking up the tape between the spindles as it is slackened, means for clamping the tape between the spindles and the roll, means for cutting off the tape between the spindles and the roll, means for rotating the spindles and causing them to turn the ends of the tapes at right angles to the part between the spindles and to disengage the said part from the means by which the slack in the tape is taken up, punches sheathed in the said spindles adapted to be driven out of the same between the notches in the ends, means for driving them out of the spindles against the tape and the box to cause them to perforate the box and insert the ends of the tape in the box, rotary gluing - brushes that rotate under the table which apply the glue to the under side of the box and rotatable wipers that turn the ends of the tape up and press them against the glue for the purpose of causing them to adhere to the box, substantially as specified.

13. In a machine for applying tapes to

boxes the combination of longitudinally movable and rotatable spindles for holding the tape and turning the ends thereof preparatory to their insertion in the box, a reciprocally-movable rack-bar held in a longitudinal groove in the table, a gripper connected therewith and adapted to be carried thereby to the right and left parallel to the spindles, means for opening the gripper when carried 5 to the left to receive the end of the tape, means for closing the same as it is carried to the right to cause it to grip the end of the tape and lay the tape under the spindles and on the part of the box to which it is to be attached, substantially as specified.

14. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable 10

rack-bar held in a longitudinal groove in the table, a gripper connected with said rack-bar and adapted to be carried thereby to the right and left parallel to the spindles, means for opening the gripper to receive the end of the tape when carried to the left, means for closing the same as it is carried to the right to 15

cause it to grip the end of the tape and to lay the tape under the spindles and on the part of the box to which it is to be attached, means for moving the gripper to the left a limited distance after the tape has been 20

secured on the box by the spindles to slacken the tape, a finger that projects between the spindles into the opening in the spindle-guide, a fork, a bar connected with the fork, an arm on the end of the bar, a finger on the arm that 25

projects between the spindles and into the opening in the spindle-guide, means for reciprocating the fork to cause it to drop the finger down to the box previous to the movement of the gripper to the right, whereby 30

the tape carried by the gripper is laid across the finger, and to lift it as the tape is slackened to take up the slack as the gripper moves to the left, substantially as specified.

15. In a machine for applying tapes to boxes the combination of longitudinally movable and rotatable spindles for holding the tape and turning the ends thereof preparatory to their insertion in the box each of said spindles having notches in its end diametrically opposite each other, a spindle-guide having an opening in its under side between the spindles, a reciprocally-movable rack-bar held in a groove in the table, a gripper connected with said rack-bar and adapted to be 45

carried thereby to the right and left parallel to the spindles, means for opening the gripper when carried to the left to receive the end of the tape, means for closing the same as it is carried to the left to cause it to grip the end 50

of the tape and lay the tape under the spindles and on the part of the box to which it is to be attached, means for moving the gripper to the left a limited distance to slacken the tape, a finger that projects between the spindles and into the opening in the spindle-guide, a fork, a bar connected with the fork, an arm on the end of the bar, a finger on the arm that 55

projects between the spindles and into the opening in the spindle-guide, means for reciprocating the fork to cause it to drop the finger down to the box previous to the movement of the gripper to the right, whereby the tape is laid across the finger, and to lift it as the tape is slackened to take up the slack as the gripper moves to the left and cause the part of the tape under the spindles to enter the notches in the spindles, means for opening the gripper to cause it to 60

release the end of the tape, and means for cutting off the length of the tape on the box held by the spindles from the part connected with the roll, substantially as specified.

16. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable 65

rack-bar in a longitudinal groove in the table, a gripper connected with said rack-bar and adapted to be carried thereby to the right and left parallel to the spindles, means for opening the gripper to cause it to grip the end of the tape and lay the tape under the spindles and on the part of the box to which it is to be attached, substantially as specified.

17. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable rack-bar in a longitudinal groove in the table, a gripper connected with said rack-bar and adapted to be carried thereby to the right, whereby the tape is laid across the finger, and to lift it to take up the slack of the tape as the gripper moves to the left and cause the parts of the tape under the spindles to enter the notches in the spindles, means for opening the gripper to cause it to 70

release the end of the tape, and means for cutting off the length of the tape on the box held by the spindles from the part connected with the roll, substantially as specified.

18. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable 75

rack-bar in a longitudinal groove in the table, a gripper connected with said rack-bar and adapted to be carried thereby to the right and left parallel to the spindles, means for opening the gripper to cause it to grip the end of the tape and lay the tape under the spindles and on the part of the box to which it is to be attached, substantially as specified.

19. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable 80

rack-bar in a longitudinal groove in the table, a gripper connected with said rack-bar and adapted to be carried thereby to the right and left parallel to the spindles, means for opening the gripper to cause it to grip the end of the tape and lay the tape under the spindles and on the part of the box to which it is to be attached, substantially as specified.

20. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable 85

rack-bar in a longitudinal groove in the table, a gripper connected with said rack-bar and adapted to be carried thereby to the right and left parallel to the spindles, means for opening the gripper to cause it to grip the end of the tape and lay the tape under the spindles and on the part of the box to which it is to be attached, substantially as specified.

21. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable 90

rack-bar in a longitudinal groove in the table, a gripper connected with said rack-bar and adapted to be carried thereby to the right and left parallel to the spindles, means for opening the gripper to cause it to grip the end of the tape and lay the tape under the spindles and on the part of the box to which it is to be attached, substantially as specified.

22. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable 95

rack-bar in a longitudinal groove in the table, a gripper connected with said rack-bar and adapted to be carried thereby to the right and left parallel to the spindles, means for opening the gripper to cause it to grip the end of the tape and lay the tape under the spindles and on the part of the box to which it is to be attached, substantially as specified.

23. In a machine for applying tapes to boxes the combination of longitudinally movable and rotatable spindles for holding the tape and turning the ends thereof preparatory to their insertion in the box, a spindle-guide having an opening in its under side between the spindles, a reciprocally-movable 100

rack-bar in a longitudinal groove in the table, a gripper connected with said rack-bar and adapted to be carried thereby to the right and left parallel to the spindles, means for opening the gripper to cause it to grip the end of the tape and lay the tape under the spindles and on the part of the box to which it is to be attached, substantially as specified.

for opening the gripper to receive the end of the tape when carried to the left, means for closing the same as it is carried to the right to cause it to grip the end of the tape and lay the tape under the spindles on the part of the box to which it is to be attached, means for moving the gripper to the left a limited distance to slacken the tape, a finger that projects between the spindles and into the opening in the spindle-guide, a fork a bar fastened to the fork, an arm on the end of the bar to which said finger is connected, means for reciprocating the fork to cause it to drop the finger to the box previous to the movement of the gripper to the right, whereby the tape is laid across a finger, and to lift it as the tape is slackened to take up the slack as the gripper moves to the left and causes the part of the tape under the spindles which is lifted up by the finger to enter the notches in the spindles, means for opening the gripper to cause it to release the end of the tape, means for cutting off the length of the tape on the box held by the spindles from the part connected with the roll, a clamp for holding the tape between the end and the roll when the part under the spindles is cut off, means for moving the said clamp, and means for rotating the spindles while bearing against the tape to cause the outside notches to bear against the ends of the tape and the inside notches to bear against the edges of the part of the tape held on the finger and thereby disconnect the latter from the finger and at the same time turn the ends of the tape at right angles to the side part, substantially as specified.

18. In a machine for applying tapes to boxes the combination of a table to support the box, means for laying the tape on the box in position to be attached thereto, a spindle-guide, hollow longitudinally movable and rotatable spindles therein each of which has notches in its end that are diametrically opposite each other, punches inserted in the spindles and adapted to be driven out of the same through guide-openings in the ends between the notches, pins connected with the punches that project up through the stems of the spindles, brackets having their upper ends connected with the ends of the pins and their lower ends held in guides, cams that bear against the upper ends of the brackets and pins by which they are driven downward and the pins caused to force the punches out of the spindles against the ends of the tape and the box thereby perforating the box and inserting the ends of the tape in the perforations, an inverted-T-shaped plate the arms of which are connected with the guides and the upper end attached to a spring whereby the punches are drawn up into the spindles after the ends of the tape are inserted in the perforations in the box, substantially as specified.

19. In a machine for applying tapes to boxes the combination of a table to support the box, means for laying the tape on the box in position to be attached thereto, a spindle-guide, hollow, longitudinally movable and rotatable spindles therein each of which has notches in its end that are diametrically opposite each other, a yoke that connects the stems of the spindles above the spindle-guide, a fork connected with said yoke, a cam and a spring for moving the fork up and down to cause the yoke to move the spindles longitudinally, pinions mounted on the stems of the spindles, forks provided with rack-teeth geared to the pinions for the purpose of rotating the same and cams for reciprocating the said forks to rotate the spindles in opposite directions, substantially as specified.

20. In a machine for applying tapes to boxes a table for the machine to support the box, means for laying the tape on the box in position to be attached thereto, a spindle-guide, longitudinally movable and rotatable spindles therein each of which has notches in its end that are diametrically opposite each other, means for moving the spindles longitudinally and rotating them in opposite directions, punches inserted in the spindles adapted to be driven out of the same through openings in the ends between the notches, means for moving the punches in and out of the spindles, mortises in the table under the spindles, gluing-brushes mounted on a shaft under the said mortises, wipers mounted on the shaft behind the gluing-brushes, a glue-tank, snail-wheels mounted thereon to take up the glue from the tank and adapted to come in contact with the glue-brushes, means for rotating the glue-brushes and means for rotating the snail-wheels whereby the glue-brushes apply the adhesive to the under side of the box and when the punches perforate the same and insert the ends of the tape the wipers turn the ends up and fasten them to the box by means of the glue on the box, substantially as specified.

21. In a machine for applying tapes to boxes the combination of hollow longitudinally movable and rotatable spindles each of which has notches in its ends that are diametrically opposite each other, means for rotating said spindles in opposite directions, means for moving the said spindles longitudinally, a table to support the box, a gripper for drawing the tape off the roll and laying it on top of the box and under the spindles said gripper connected with a reciprocally-movable bar held in a longitudinal groove in the table and consisting of a fixed jaw provided with a spring-bolt having a hook on its end, a movable jaw provided with a V-shaped notch which is engaged by the spring-bolt to hold the movable jaw open and a toe, a spring for closing said jaw, a vertically-reciprocating

fork to open the jaw of the gripper, a finger which when the rack-bar moves to the left engages the hook on the spring-bolt and withdraws the same from the V-shaped notch in the movable jaw thereby allowing the movable jaw to close and grip the end of the tape, substantially as specified.

22. In a machine for applying tapes to boxes the combination of longitudinally movable and rotatable spindles each of which has notches in its end that are diametrically each other, guides for the spindles, means for moving the said spindles longitudinally, means for rotating the spindles in opposite directions, a table to support the box, a gripper for drawing the tape off the roll and laying it on top of the box and under the spindles, said gripper connected with a reciprocally-movable bar held in a longitudinal groove in the table and consisting of a fixed jaw provided with a spring-bolt having a hook on its end, a movable jaw provided with a V-shaped notch which is engaged by the spring-bolt to hold the movable jaw open and a toe, a spring for closing said jaw, a ver-

tically-reciprocating fork to open the jaw when moved to the left to take the end of the tape and when moved back after laying the tape on the box to slacken the tape, a finger which when the rack-bar moves to the left engages the hook on the spring-bolt and withdraw the same from the V-shaped notch in the movable jaw thereby releasing the movable jaw to allow it to close and grip the end of the tape, a rectangular arm having a groove in its top to serve as a guide for the tape, a knife-edge on said arm, a vertically-movable knife for severing the tape and a vertically-movable clamp to hold the tape between the end and the roll after the part under the spindle is cut off, substantially as specified.

In testimony that I claim the invention above set forth I have affixed my signature in presence of two witnesses.

JACOB HUETHER.
